WEAR POINT FOR AGRICULTURAL FERTILIZER SHANK

Charles J. Clark, 6609 Washington N. 99208, and
Charles Bedford, 11315 Galahad Drive N. 99218,
both of Spokane, Wash.

Filed Apr. 18, 1974, Ser. No. 461,990

Term of patent 14 years

Int. Cl. D15—03

U.S. Cl. D39—1 R

FIG. 6

FIG. 1 is a side elevation view of a wear point for agricultural fertilizer shank, the opposite side being a mirror image;

FIG. 2 is a top view;

FIG. 3 is a bottom view;

FIG. 4 is a view taken along line 4—4 in FIG. 1;

FIG. 5 is a view taken along line 5—5 in FIG. 1; and FIG. 6 is a perspective viewed from the top and rear of FIG. 1.

We claim:

The ornamental design for a wear point for agricultural fertilizer shank, as shown and described.
